HAND MIRROR

Max H. Storch, Bell Harbor, Long Island, N. Y.

Application February 25, 1938, Serial No. 192,456

1 Claim. (Cl. 306—41)

This invention relates to devices such as hand mirrors, brushes and the like.

One object of the invention is to provide a device of the character described having an inexpensive handle structure comprising a shank and handle sleeved thereon in improved inter-engagement.

Heretofore, I have proposed the provision of a shank having transverse corrugations to afford a spring engagement with the sleeve on forcing the latter over the shank. This structure, which had for its main purpose the reduction of cost of making the device such as hand mirrors, and the like, possessed one important drawback. This resided in the fact that the handles vary in size, and it appears that the ornamental tubular stock purchased on the market is not made according to standard diameters. Hence the corrugated shank might be too large at times, and in other instances, too small to properly fit the shank. In ornamental hand mirrors a great many different designs are produced to order and hence this was an obstacle to economical manufacture. Nor did the corrugations lend themselves readily to a decrease or increase in size, with any degree of accuracy, and without distortion of the shank.

Another drawback of the corrugated shank was that its range of use was limited in that it could not be used in special handles which are cast open or in skeletonized form to receive enameled or other decorative panels. With the present invention, the shank is maintained flat and thin so that it can be operatively accommodated in such a handle.

Hence it is a further object of the invention to provide a resiliently engaging handle shank which can be made in a simple stamping operation and which can be readily adjusted to suit handles of varying sizes, and which constitutes preferably a thin flat structure that can be readily used in cast flat handles when desired.

Heretofore hand mirrors of the channel frame type have been provided with a considerable thickness of paper board backing. With the present invention, the cost of such backing is largely eliminated and also the cost of cutting and handling the same, the invention providing a stiffener plate for the bendable frame, formed with integral resilient tongues adapted to act on the mirror by bearing on a sheet of backing paper or other material.

The invention also provides improved means for securing the handle shank to the stiffener plate without welding, thus permitting the use of a thinner plate and saving cost in manufacture.

A related object of the invention is to furnish improved means for anchoring the handle shank relative to the plate and frame to reinforce the handle shank against longitudinal strain in its securing to the stiffener plate.

Another object of the invention is to provide improved means for anchoring the tongue ends of the frame, in association with the handle and the ferrule or ring.

Other objects and advantages of the invention will become apparent as the specification proceeds.

With the aforesaid objects in view, the invention consists in the novel combinations and arrangements of parts hereinafter described in their preferred embodiments, pointed out in the subjoined claim, and illustrated in the annexed drawing, wherein like parts are designated by the same reference characters throughout the several views.

In the drawing:

Figure 1 is a plan view of a device embodying the invention, with parts removed to show the handle structure.

Fig. 2 is an enlarged sectional view of the handle taken on line 2—2 of Fig. 1.

Fig. 3 is a fragmentary perspective view of the shank showing the method of adjusting the same.

Fig. 4 is an enlarged sectional view taken on line 4—4 of Fig. 1.

Fig. 5 is a plan view of the shank and stiffener plate unit.

Fig. 6 is a fragmentary view of a step in assembling the frame end tongues with the shank.

Fig. 7 is a sectional view taken on line 7—7 of Fig. 6.

Fig. 8 is a side view of the ring or ferrule.

Fig. 9 is a view of the washer or holder for the frame tongues.

Fig. 10 is an enlarged fragmentary sectional view of details of the assembly.

Fig. 11 is a fragmentary plan view of a modified device embodying the invention, with the handle open.

Figs. 12 and 13 are sectional views taken on lines 12—12 and 13—13 of Figs. 11.

Fig. 14 is a bottom plan view of an ornamental closure plate for the handle.

The advantages of the invention as here outlined are best realized when all of its features and instrumentalities are combined in one and the same structure, but, useful devices may be produced embodying less than the whole.

It will be obvious to those skilled in the art to which the invention appertains, that the same

may be incorporated in several different constructions. The accompanying drawing, therefore, is submitted merely as showing the preferred exemplification of the invention.

5 Referring in detail to the drawing, 15 denotes a handle structure embodying the invention, and 16 denotes a device such as a hand mirror embodying the invention.

10 The handle structure 15 may comprise a shank 17 consisting of a flat thin strip of material that is initially of uniform width, and which is of uniform thickness. The material of the shank may be relatively rigid and yet yieldable or resilient to a suitable degree. Preferably the shank 15 is made of soft or malleable iron standard stock. In such a strip of material is formed a longitudinal slot 18 which is thus adapted to be cut by a simple stamping operation. Now the slotted portion 19 is expanded or enlarged in width to afford a loop-like spring. Then a tubular handle 20 is forced over the shank so as to be grippingly frictionally held by the slotted portion 19. It is noted that the shank 17 is otherwise freely fittingly received in the handle 20 with a slight clearance. This serves to center the handle on the shank. Should the handle 20 be slightly too large, the portion 19 can be expanded to suit as by any wedging tool 21 shown in Fig. 3. If the handle tube be too small, the portion 19 may be contracted by a clamping or other device. However, there is sufficient resilience in the shank to engage handles of slightly varying sizes.

15 While the handle structure 15 can be used with any kind of device, it has particular advantage with a device having a split article holding channel rim or frame 22, in which are disposed a mirror 23, a back plate 24 and a stiffener plate 25. The latter may be marginally concaved along its edges and may have a series of struck out tongues 26 for resiliently bearing on a paper backing plate 27 for the mirror. Thus the cost of the hand mirror is considerably reduced, the assembling rendered easier, and the mirror is reliably held in position in a light weight structure, without the use of many paper board filler sheets.

20 As shown in Fig. 5, the shank extends outward of the stiffener plate 25 and is secured thereto. Tongues 28 are struck from the plate 25 and are 50 by pressed means. For example, a pair of tongues 28 are struck from the plate 25 and are received in the holes 29 formed in the shank. These tongues 28 are then bent over on the shank as shown at 28a and their free end portions are 55 partially bent into the adjacent holes 30 of the shank to rigidly secure the latter. At 31 a clearance cut out may be provided for the shank.

25 Formed in the side edges of the shank 17 are a plurality of recesses 32 for receiving the opposite end tongues 33 which are integrally formed with the frame 22 at the ends thereof. Desirably, these recesses are arranged also to receive therein portions of the back of the channel as is clearly shown at 34 in Fig. 10. A conventional ferrule or ring 35 is sleeved over the shank 17 and around the tongues 33. Fittingly received

in the member 35, is a U-shaped washer or element 36, the arms of which snugly hold the tongues 33 in the recesses 32. It is noted that the member 35 can receive the shank 17 whereas the element 36 is too small for that purpose, 5 but is laterally applied over the tongues 33 and then slipped into the member 35.

10 It will be observed that the arrangement shown at 32, 33, 34, 35 and 36 affords a particularly secure and reliable lock for the frame 10 tongues 33. An additional advantage is that the structure is small and compact, and that the shank 17 seats on the frame at 34 to restrain outward movement of the shank. Inward movement of the shank 17 may be restrained by a 15 struck out lug 37 in the plate 25, this lug presenting a free edge in abutment with the end of the shank. Thus the shank is not only held by the tongues 28a but is longitudinally reinforced also at 34 and 37.

20 The handle 20 is now forcibly sleeved over the shank 17, so that its upper free end seats in the ferrule 35 and against the element 36 so as to lock the assembly, while restraining lateral shifting of the handle on the shank. If desired, 25 added rigidity may be obtained by providing a transverse corrugation 38 in the shank remote from the slotted portion.

25 In Figs. 11 to 14 is shown a modified device 40 embodying the invention and illustrating the 30 application of the invention to a flat skeleton cast handle 41 having a large side opening 42 for receiving an ornamental closure plate 43. The handle may be formed with longitudinal 35 parallel ribs 44 therein providing a shallow passage for the shank 17 with its slotted portion 19 gripping the ribs frictionally. Also formed in the handle are seating portions 45, 46 having bores 47 to press fittingly receive the pins 48 of the plate 43 with the latter resting on the 40 seating portions and on the ribs 44. The corrugation 38 may be omitted in this modification, but the device 40 may otherwise be like the device 16.

35 I claim:

40 A device for a mirror including a member, a flat sheet metal shank connected thereto having a portion slotted lengthwise of the shank to afford longitudinal strip elements, the latter being initially moved apart with the width of said slotted portion being greater than that of the 50 rest of the shank, said strip elements being laterally resilient, and a tubular handle having a longitudinal cylindrical passage of a diameter greater in size than the width of the shank, said shank extending into the passage with the strip elements tending to expand for powerfully frictionally gripping the sides of said passage to retain the handle on said shank, said shank having a transverse corrugation adjacent to the junction of the member and the shank remote from the slotted portion to thus increase the size of the shank, said corrugation being in contact with an adjacent end of said handle within said passage to center the shank in the handle. 55

60 MAX H. STORCH.
